TUMBLER TYPE HOT-AIR DRIER HAVING A
CASING BULKHEADPeter Eduard Geldhof, St. Joseph, Mich., assignor
to Nineteen Hundred Corporation, St. Joseph,
Mich., a corporation of New York

Application June 7, 1946, Serial No. 675,077

10 Claims. (Cl. 34—82)

1

This invention relates to a clothes drier, and more particularly to a small, compact unitary clothes drier of the type which is suitable for ordinary household use in conjunction with any laundry machine or washing apparatus.

One type of clothes drier which is supplied for household use includes a rotating drum through which heated air is circulated. The rotating drum is mounted within a closed housing.

It is one of the principal features and objects of the present invention to provide a novel clothes drier of this general category which gives greatly improved results with a minimum expenditure of energy.

A further object of the present invention is to provide a novel bulk head drier.

Another object of the present invention is to provide novel means for heating and circulating air in a clothes or article drier.

A still further object of the present invention is to provide a clothes drier in which air is drawn over a heating means and then through an article containing drum by suction apparatus located at the outlet.

Another and still further object of the present invention is to provide a novel cabinet or housing for drying apparatus.

The novel features which I believe to be characteristic of my invention are set forth with particularity in the appended claims. My invention itself, however, both as to its organization, manner of construction and method of operation, together with further objects and advantages thereof, may best be understood by reference to the following description, taken in connection with the accompanying drawings, in which:

Figure 1 is an isometric view of a clothes drier embodying the novel features and characteristics of the present invention, looking downwardly thereon from the left front corner thereof;

Figure 2 is an isometric view of the clothes drier shown in Figure 1 but looking down on it from the rear corner thereof which is located diagonally opposite from the corner from which the view in Figure 1 is taken;

Figure 3 is a vertical sectional view, on an enlarged scale, as taken along the line III—III of Figure 1;

Figure 4 is a vertical sectional view as taken along the line IV—IV of Figure 3;

Figure 5 is a vertical sectional view through the machine taken along the line V—V of Figure 1; and

Figure 6 is a fragmentary sectional view of

the upper right corner of Figure 4 illustrating a modified form of the present invention.

As shown in the embodiment of the invention illustrated in Figures 1 to 5 of the drawings, the clothes drier 10 includes an outer shell or cabinet 11 in which is mounted a rotating drum 12 which is arranged to receive clothes or other articles to be dried.

The drum 12 is mounted for rotation about a horizontal axis and is arranged to be driven by a motor 13 through a belt drive 14.

The cabinet 11 of the drier 10 is provided with an opening in the front wall thereof opposite the drum 12 which opening is defined by a flange 15, which extends axially rearwardly. This opening as defined by the flange 15 is sufficiently large to introduce clothes through the open end of the drum 12 which is defined by the flange 16 on the drum 12. The two flanges 15 and 16 are disposed in overlapping spaced relationship, as is clearly shown in Figure 4 of the drawings, and a felt ring 17 is secured to the flange 16 by means of a band 18. The felt ring 17 extends into rubbing engagement with the front wall 19 of the cabinet 11.

The opening 15 in the cabinet 11 is arranged to be closed by means of an imperforate door 20 suitably mounted for opening and closing movement, such as by hinge means or the like (not shown).

Radially outwardly of the flange 16 on the drum 12, the forward wall 21 of the drum 12 is provided with a series of openings 22 therein through which air may pass from the interior of the drum into the region between the forward end of the drum and the front wall 19 of the housing 11.

As is shown in Figure 5 of the drawings, the rear end of the drum 12 is made up of an imperforate wall 103 having a relatively large central opening therein defined by an axially rearwardly extending flange 102. Within this opening defined by the flange 102 is a screen member 63 having an axially rearwardly turned peripheral edge 101 for nested engagement with the flange 102.

Heated air is forced through the rear screen 63 of the drum 12, through the drum and then out through the front annular portion 21 which makes up the front wall of the drum 12. It will be noted that the air does not pass out through the large central opening as defined by the edge 16 on the drum 12 due to the fact that an imperforate door 20 covers this opening.

One of the distinctive features of the present invention is to provide a bulk head 27 which is

55

in the form of a wall surrounding the drum 12 and spaced from the forward wall 19 within the cabinet 11. The bulk head 27 is secured to the side walls of the cabinet 11 by means of angle brackets 28, these brackets 28 being welded or otherwise suitably secured to the side walls of the cabinet 11, and bolted as at 29 to the bulk head 27. As may be seen best in Figure 5 of the drawings, the bulk head 27 has a large opening in the center thereof through which the forward edge of the drum extends. This large opening of the bulk head 27 is defined by a rearwardly facing channel flange 31, which includes a forwardly extending flange portion 32, a radially inwardly extending flange portion 33, and a rearwardly extending flange portion 34.

In order to obtain an air seal between the bulk head 27 and the rotating drum 12, a felt ring 35 is secured to the rear face of the bulk head 27 by means of a clamping band 36. This felt ring 35 extends into wiping engagement with the outer surface of the drum 12.

From the above description it will be apparent that a sealed chamber is provided into which the air passing from the drum escapes and from which there is no egress except in the manner now to be described.

Two pipes extend from this chamber between the bulk head 27 and the front wall 19 of the housing 11, which two pipes are identified by the reference numerals 37 and 38. The pipe 37 is near the top of the housing 11 and to one side of the drum 12. It extends directly from the bulk head 27 rearwardly and out through the rear wall 39 of the housing 11. The rear end of the pipe 37 is capped with a filter unit 40 in the form of a drum having a peripheral surface 41 in the form of a screen and solid end walls 42 and 43.

The pipe 38 is located near the bottom of the housing 11 and extends rearwardly from the bulk head 27 to a region near the rear of the housing 11 and then upwardly where it connects as at 44 with the top pipe 37. Air passing through the drum 12 thus passes out through the openings 22 in the front wall of the drum 12 into the chamber between the bulk head 27 and the front wall 19, and then out through the pipes 37 and 38 and the filter unit 40.

The air intake for the housing is provided by a series of holes 45 located in the rear wall 39 of the housing 11 and directly opposite the rear end of the shroud 46 which lies between the drum 12 and the rear wall 39 and surrounds the heating and blowing means. The heating and blowing means may be any suitable means for raising the temperature of the air and causing the air to flow through the drum 12.

One particular form of heating and blowing means which has been found extremely satisfactory in practice is described and claimed in the pending application of Peter Eduard Geldhof and Charles E. Morgenstern entitled "Clothes Drier," U. S. Serial No. 652,863, filed March 8, 1946, now Patent No. 2,503,329, and assigned to the same assignee as the present invention. The essential features of this structure may be seen best in Figure 5 of the drawings which will now be described.

The rotatable drum 12, the heating means and the air circulating means are all mounted on a single pedestal 47 which is in the form of an up-standing tubular member 48 having a pair of divergent legs 49. The diverging legs 49 are made up of a single channel-shaped bracket which is wrapped around the tubular member 48 and

welded or otherwise suitably secured thereto. It will be observed that the legs 49 which form this bracket extend out well beneath the rotating drum 12, and thus supply a satisfactory rigid base for the rotating assembly. The legs 49 rest on the base plate 50 of the cabinet 11. The base plate 50 has a downturned edge flange 51 which is welded or otherwise suitably secured to the walls of the housing 11.

10 A bearing support sleeve 52 is seated on the top of the tubular member 48, the latter being cut away so as to fit snugly around a portion of the sleeve. The sleeve 52 may be welded or otherwise suitably secured to the top of the tubular member 48.

Within the tubular sleeve 52 are disposed two bearing sleeves 53 and 54 which may, by way of example, be porous metal, lubricant impregnated bearing sleeves. These bearing sleeves 53 and 54 are disposed at opposite ends of the stationary sleeve 52. In order to provide additional lubricant, a wick formed of felt or other suitable material 55 is carried in a small tube 56 which is secured to the main sleeve 52. This wick 55 extends down and into the space between the inner ends of the bearing sleeves 53 and 54.

20 The rotating drum 12 is provided with a frame or spider in the form of three radially extending supporting arms 57, 58 and 59. The inner ends of the arms 57, 58 and 59 are secured to a hub 60 which is pinned as at 61 to a shaft 62 extending therethrough and abutting the rear perforated panel or screen member 63 of the drum 12. Each individual arm 57, 58 and 59 is pinned to the hub 60 by a pin 64.

25 Each arm 57, 58 and 59 is formed of a sheet metal tube 65 which is flattened near its outer end, as at 66. The flattened portion 66 is bolted to the drum 12 by a small bolt 67 and by a large bolt 68 which extends clear through the drum from one end to the other. The points at which the outer ends of the arms 57, 58 and 59 are secured are directly opposite the points where the large fins 69, 70 and 71 lie, respectively. These fins 69, 70 and 71 are formed of sheet metal and are bolted to the outer peripheral wall 30' of the drum 12 as at 72, and are each formed of a sheet which provides a fin which is relatively thick and which extends radially inwardly for a substantial distance from the inner surface of the outer peripheral wall 30' of the drum 12.

30 These fins serve the dual purpose of providing means for tumbling the clothes within the drum and at the same time providing stiffening means for stiffening and reinforcing the entire drum.

35 The shaft 62 carried by the hub 60 extends back through the bearings 53 and 54 which are carried in the sleeve 52 at the top of the pedestal 47. The shaft 62 is somewhat longer than the sleeve 52, and accordingly extends out the rear end of the sleeve 52.

40 A pulley wheel 73 carried on a hub 74 is secured to the outer end of the shaft 62. The hub 74 is secured to the shaft 62 by means of a set screw 75, so that there is no relative rotation therebetween.

45 Between the sleeve 52 and the pulley 73, a combination fan, hub and pulley 76 is mounted for free rotation about the shaft 62. To this end, a bearing sleeve 77 is provided in the hub 76, and this bearing 77 presents a bearing surface to the shaft 62 for rotation therearound.

The bearing 71 may, for example, be a porous metal, lubricant impregnated bearing, the lubricant being supplied thereto from a wick 78 retained in the hub 76.

The hub 76 is also provided with a recessed forward face and shoulder which retains a sealing ring 79 in conjunction with the fan blade mounting ring 80. The fan blade mounting ring 80 is riveted or otherwise suitably secured as at 81 to the hub 76. A plurality of arms 82 extend out from the mounting ring 80. These arms 82 are provided with fan blades 83 at their outer ends, which are riveted or otherwise suitably secured thereto as at 84. This arrangement enables the fan to be driven at a speed which is many times the speed of rotation of the rotating drum 12.

The motor 13 is arranged to drive both the fan and drum. This motor 13 is mounted in a bracket 85 (see Figure 3) which is secured to the base 50 of the cabinet 11. The armature shaft 86 of the motor is provided with a drive pulley 87. Directly to the rear of the pedestal 43 is a bracket 88 which is secured to the base panel 50 of the cabinet 11. This bracket 88 carries a short stub shaft 89 on which is mounted a hub 90 for free rotation. The hub 90 is provided with a bearing sleeve 91 which may conveniently be of a porous metal, lubricant impregnated type. A wick 92 is provided in a recess in the hub 90 to supply lubricant to the bearing sleeve 91. The shaft 89 is threaded at its inner end in order that it may be secured by complementally threaded nut 93 to the bracket 88.

The hub 90 carries a large metal pulley 94 which is rigidly secured thereon in any suitable manner so that there is no rotation between the pulley 94 and the hub 90. The hub 90 is also provided with a V-shaped annular groove 95 which lies in the same plane as the large pulley 73 on the shaft 62. The large pulley 94 on the hub 90 lies in the same plane as the portion of the hub 76 which is provided with a V-shaped notch 96, as well as in the same plane as the motor pulley 87. One V-shaped belt 97 extends around the motor pulley 87 and the pulley 94, in the V-shaped annular groove in the hub 76. A second V-shaped belt 14 extends around the large pulley 73 and around the hub 92 in the groove 95 thereof. Since the pulley 94 is substantially larger than the pulley 87, a speed reduction occurs in the drive from the motor pulley to the pulley 94. Since the pulley portion 95 of the hub 90 has no rotation with respect to the pulley 94, it will be seen that a further speed reduction occurs between the hub 90 and the large pulley 73 secured to the drum axle 62.

It will further be noted that the pulley portion 96 of the hub 76 is only slightly larger than the motor pulley 87 and hence the fan 83 is driven at a much higher speed than is the drum 12, although both are driven from the same motor with the motor running at a single speed.

In order to properly direct the air which is set into motion by rotation of the fan 83, a large sheet metal shroud 46 in substantially the form of a tubular casing member is mounted on the pedestal by means of a V-shaped bracket 98 (see Figure 3). The V-shaped bracket 98 has a base portion 99 which is secured to the top of the sleeve 52 by the threaded end of a small sleeve 56 which is threaded into the large sleeve 52. The outer ends of the V-shaped bracket 99 are secured to the shroud 46 in any suitable manner (not shown).

It will be noted that the shroud 46 terminates

just short of the rearwardmost portion of the rotating drum 12 and is substantially of the same diameter as the perforated panel or screen member 63. It will further be observed, that the perforated panel or screen member 63 has a rearwardly extending peripheral flange 101 which is seated in a rearwardly extending opening defining flange 102 of the imperforate rear wall 103 of the drum 12. The shroud 46 extends up to a position in close proximity to the rearwardly extending flanges 101 and 102 of the rotating drum 12. It will furthermore be observed that the diameter of the tubular shroud 46 is substantially the same as the diameter of the circular opening formed by the flange 102, and thereby confines and directs the air from the fan 83 directly into the rear of the rotating drum 12.

A second conically shaped shroud 104 is provided interiorly of the shroud 46 to form a heat-reflector baffle plate for the heating means 105. This conically shaped shroud or reflector member 104 extends over the bearings 53 and 54 up to a position in close proximity to the fan blade 83, the small end of the conically shaped member being nearest the drum 12.

The heating means 105 above referred to is located between the tubular shroud 46 and the conically shaped shroud or heat reflector 104. This heating element 105 is formed of two heating coils 106 and 107 which are concentrically disposed and serially connected as shown in Figure 3. Power for these serially connected heating elements 106 and 107 is supplied through conductors 108 and 109.

The heating elements 106 and 107 are mounted in a plurality of radially extending porcelain or other suitable electric insulating material fingers 110 which are carried on the shroud 46. Each finger has a pair of holes 111 and 112 therein through which the heating elements 106 and 107 extend, respectively, and are supported thereby.

The operation of the clothes drier illustrated in Figures 1 to 5 of the drawings will now be described. The door 20 is opened and clothes are inserted into the drum 12. The door 20 is then closed and the motor 13 energized. The power supply conductors 108 and 109 are connected to a suitable source of electric energy, such, for example, as a source of power having 220 volts.

Air is drawn through the rear openings 45 in the housing 11 by the fan 83 and is forced over the heating coils 106 and 107, and thence through the drum 12. Heat is carried by the air so circulated and is also transferred by radiation from the conical reflector 104. The air passing through the drum 12 passes out the forward wall 21 of the drum 12 through the openings 22 into the region between the bulk head 27 and the front wall 19. Since it has no place else to escape, it then passes back through the two pipes 37 and 38, and finally out through the filter unit 40.

Any lint which may be caught up in the air stream as it passes through the drum 12 is caught in the screen 41 of the filter unit 40, and thus separated from the air before it is returned to the room. From time to time, the filter unit 40 may be slipped off the end of the pipe 37 and cleaned.

A modified form of the present invention is illustrated in Figure 6 of the drawings. More particularly, Figure 6 illustrates that a suction fan may be provided at the outlet of the air duct 37 rather than in the shroud 46, if desired. As shown in Figures 6, a sirocco fan 113 is mounted by means of suitable brackets 113'

on the rear wall 38 of the housing 11. Any suitable means may be provided for driving this fan, such, for example, as a small motor 114 mounted by mounting bolts 115 to the housing of the fan 113. The housing of the fan 113 (which may be in the form of a scroll casing) has an outlet duct 116 with a removable filter screen 117 therein.

When the suction fan 113 is used, the fan 83 may be eliminated from within the shroud 46.

While I have shown certain particular embodiments of my invention, it will, of course, be understood that I do not wish to be limited thereto, since many modifications may be made, and I, therefore, contemplate by the appended claims to cover all such modifications as fall within the true spirit and scope of my invention.

I claim as my invention:

1. A drier comprising a cabinet, a drum mounted in said cabinet for rotation about substantially a horizontal axis, a bulk head in said cabinet surrounding said drum, said bulk head dividing said cabinet into a rear air chamber and a separate front air chamber which are in communication with each other only through said drum, said drum having an imperforate peripheral wall and having air openings in the front and rear walls thereof, means for heating air in said rear chamber, means for circulating heated air from said rear chamber through said drum into said front chamber, a discharge pipe in one of the upper corners of said cabinet extending from said front chamber through said bulk head and back out through the rear wall of said cabinet, and a second discharge pipe extending from said first chamber through said bulk head in proximity to the bottom of said cabinet to a point in proximity to the rear wall of said cabinet and then upwardly into communication with said first discharge pipe whereby heated air discharged from said front chamber transfers some of its heat to the fresh air being drawn into said rear chamber.

2. A drier comprising a cabinet, a drum mounted in said cabinet for rotation about substantially a horizontal axis, a bulk head in said cabinet surrounding said drum, said bulk head dividing said cabinet into a rear air chamber and a separate front air chamber which are in communication with each other only through said drum, said drum having an imperforate peripheral wall and having air openings in the front and rear walls thereof, means for heating air in said rear chamber, means for circulating heated air from said rear chamber through said drum into said front chamber, a discharge pipe in one of the upper corners of said cabinet extending from said front chamber through said bulk head and back out through the rear wall of said cabinet, and a second discharge pipe extending from said first chamber through said bulk head in proximity to the bottom of said cabinet to a point in proximity to the rear wall of said cabinet and then upwardly into communication with said first discharge pipe whereby heated air discharged from said front chamber transfers some of its heat to the fresh air being drawn into said rear chamber, and a filter drum detachably mounted on the end of said first discharge pipe exteriorly of said cabinet, said filter drum including two imperforate end walls and a perforated peripheral wall, one of said imperforate end walls having an opening therein arranged to receive the end of the first discharge pipe, said

perforate peripheral wall being arranged to separate out lint and other foreign particles in the discharged air.

3. A clothes drier comprising a cabinet, a drum mounted in said cabinet for rotation about substantially a horizontal axis, an imperforate door in the front wall of said cabinet through which clothes may be introduced and removed from said drum, said drum having a central opening in the front wall thereof through which clothes may be introduced and removed when said door is opened, a bulk head in said cabinet surrounding said drum and in proximity to the front end of said drum, a sealing gasket on said bulk head engaging said drum whereby said bulk head separates said cabinet into two separate air chambers, said drum having an imperforate peripheral wall, the front wall of said drum having air openings therein radially outwardly of said clothes-receiving opening, the rear wall of said drum having an imperforate outer annular portion and a perforate central portion, a shroud disposed rearwardly of said perforate central portion of the rear wall of said drum and in close proximity thereto, heating means within said shroud, and air circulating means within said shroud for circulating air over said heating means and through said drum, and at least one discharge pipe extending from the air chamber in the front of said cabinet through said bulk head and back through the air chamber in the rear of said cabinet through the exterior wall of said cabinet.

4. A drier comprising a cabinet defining a chamber and having a front wall with an opening to receive clothes or the like, a drum having openings in its opposite ends and mounted in said cabinet for rotation about an axis substantially perpendicular to the plane of said wall, an inwardly extending ring disposed across the front portion of said drum, said ring having openings for the passage of air and extending inwardly to approximate alignment with said first opening, elements forming an imperforate tube from said first opening to the opening formed by said ring, a bulk head in said cabinet forming an air seal between said drum and said cabinet to form a chamber in conjunction with said front wall, said chamber being in communication with the interior of said drum through said openings in said ring, said cabinet defining an air intake opening for the intake of air to the rear portion of said drum and having elements to define air passageways from said chamber to the exterior of said cabinet, and means for circulating air through said drum from said air intake openings to said last chamber.

5. A drier comprising a cabinet defining a chamber and having a front wall with an opening to receive clothes or the like, a drum having openings in its opposite ends and mounted in said cabinet for rotation about an axis substantially perpendicular to the plane of said wall, an inwardly extending ring disposed across the front portion of said drum, said ring having openings for the passage of air and extending inwardly to approximate alignment with said first opening, elements forming an imperforate tube from said first opening to the opening formed by said ring, a bulk head in said cabinet forming an air seal between said drum and said cabinet to form a chamber in conjunction with said front wall, means defining a passageway from the interior of said cabinet to the rear portion of said drum, heating elements disposed in said passageway to

heat air as it passes therethrough, said cabinet having elements to define air passageways from said chamber to the exterior of said cabinet, and means for circulating air through said drum from said passageway to said last chamber.

6. A drier comprising a cabinet defining a chamber and having a first wall with an opening to receive clothes or the like and a second wall, a drum having openings in its opposite ends and mounted in said cabinet for rotation about an axis substantially perpendicular to the plane of said first wall, an inwardly extending ring disposed across the front portion of said drum, said ring having openings for the passage of air and extending inwardly to approximate alignment with said first opening, elements to form an imperforate tube extending from said first opening to the opening formed by said ring, a bulk head in said cabinet forming an air seal between said drum and said cabinet to form a chamber in conjunction with said first wall, means defining a pathway from said second wall to the rear portion of said drum, heating elements disposed in said pathway to heat air as it passes therethrough, said cabinet further having elements defining air passages through the interior thereof and extending from the said last chamber to said second wall and means for circulating air through said drum from said passageway to said last chamber.

7. A drier comprising a cabinet defining a chamber and having a front wall with an opening to receive clothes or the like, said opening having an inwardly extending cylindrical flange, a drum having openings in its opposite ends and mounted in said cabinet for rotation about an axis substantially perpendicular to the plane of said front wall and in alignment with the center of the inward end of said flange, an inwardly extending ring disposed across the front portion of said drum, said ring having openings for the passage of air and extending radially inwardly to approximate alignment with said first opening, said ring having a forwardly extending cylindrical flange to mate said first flange and define a substantially imperforate tube, a bulk head in said cabinet forming an air seal between said drum and said cabinet to form a chamber in conjunction with said front wall, said chamber being in communication with the interior of said drum through said openings in said ring, said cabinet defining an air intake opening for the intake of air to the rear portion of said drum and having elements to define air passageways from said chamber to the exterior of said cabinet, and means for circulating air through said drum from said air intake openings to said last chamber.

8. A clothes drier including a cabinet having spaced walls, a drum having an imperforate cylindrical wall and openings in its opposite ends and disposed in said cabinet, a substantially imperforate bulk head extending from said drum to said cabinet to form a first chamber in conjunction with the first one of said walls and a second chamber in conjunction with the second of said walls, said first chamber being in communication with the interior of said drum through one end thereof, elements defining an air path-

way from within said second chamber to the other end of said drum, and elements defining a return air pathway from said first chamber through said cabinet and out through a wall of said cabinet.

5 9. A clothes drier including a cabinet having spaced walls, a drum having an imperforate cylindrical wall and openings in its opposite ends and disposed in said cabinet, a substantially imperforate bulk head extending from said drum to said cabinet to form a first chamber in conjunction with the first one of said walls and a second chamber in conjunction with the second of said walls, said first chamber being in communication with the interior of said drum through one end thereof, elements defining an air pathway from within said second chamber to the other end of said drum, and a pipe extending from said bulk head to said second wall to define a return air pathway from said first chamber through said cabinet and out through a wall of said cabinet.

10 10. A clothes drier including a cabinet having spaced walls, a drum enclosed by said cabinet and mounted therein for rotation about a horizontal axis, a motor mounted within said cabinet, means driven by said motor for rotatably driving said drum, said drum having an imperforate cylindrical wall with perforate wall portions at its opposite ends, a substantially imperforate bulkhead extending from the wall of said cabinet to said drum and forming a partition dividing said cabinet into two chambers, one being in communication with the interior of said drum through a wall of said cabinet and one end of said drum, the other being in communication with the atmosphere through the opposite end of said drum, air-circulating means within said cabinet for establishing a circulation of air from the atmosphere into said one end of said drum chamber and through said drum to said other chamber and out said cabinet to the atmosphere, means driven by said motor for driving said air-circulating means, and a return passageway element defining an air passageway from said second chamber in communication with the opposite end of said drum and out through said bulkhead and a wall of the cabinet.

PETER EDUARD GELDHOF.
